185,591

ELECTRIC LAMP

David Borowitz, Chicago, Ill.

Application December 29, 1958, Serial No. 53,942

Term of patent 7 years

(Cl. D48—20)

Fig. 1 is a front elevational view of an electric lamp showing my new design;

Fig. 2 is a top plan view thereof;

Fig. 3 is a fragmentary sectional view taken along the line 3—3 of Fig. 1 and looking in the direction of the arrows;

Fig. 4 is a fragmentary sectional view taken along the line 4—4 of Fig. 1 and looking in the direction of the arrows; and

Fig. 5 is a sectional view taken along the line 5—5 of Fig. 1 and looking in the direction of the arrows.

The light bulb socket is shown in dotted lines in Fig. 2 for illustrative purposes only.

I claim:

The ornamental design for an electric lamp, substantially as shown and described.
